SEALING STRIP AND STRUCTURE WITH
SEALING STRIP

William F. Fuqua, Canton, Ohio

Application September 14, 1944, Serial No. 554,078

3 Claims. (Cl. 20—69)

1

My invention relates in general to sealing strips and structures with sealing strips, and more particularly my invention relates to combinations including frames forming and extending about openings, such as door frames, window frames, storm sash frames, chest or box top frames, and the like, closures fitting in or across the frame openings, the closures being such as doors, windows, storm sashes, chest or box tops, and sealing strips on the frames or closures for sealing the closures in or across the frames when the closures are in the closed position.

Also my invention relates to siding, paneling, and other building or structural combinations, where it is desirable to provide sealing strips between individual pieces or elements.

My present invention constitutes improvements in the Sealing strips and structures with sealing strips, set forth in my prior application for United States Letters Patent, filed June 12, 1944, Serial No. 539,957.

In my said prior application, I disclose broadly in one of two overlapping pieces or elements, a longitudinally extending groove in which is self-engagingly fitted a longitudinally extending sealing strip preferably formed of bronze or similar resilient metal, the sealing strip having an unsymmetrical U transverse cross section and including laterally spaced leg walls, one leg wall being narrower than the other and being located entirely in the groove, and the other broader leg wall extending in sealing and overlapping abutment with the other piece or element.

The objects of the present invention include the provision of an improved form of sealing strip having an unsymmetrical U transverse cross section, as compared with the form of such sealing strip set forth in my said prior application, Serial No. 539,957, whereby the improved sealing strip may be produced and used with somewhat greater economy and facility than the sealing strip of my said prior application.

Further objects of the present invention include the provision of improved combinations including overlapping structural or building pieces or elements and the improved sealing strips for sealing the overlapping pieces or elements.

The foregoing and other objects are attained by the sealing strips, structures, pieces, elements, members, units, parts, combinations, and sub-combinations, which comprise the present invention, the nature of which is set forth in the following general statement, and preferred embodiments of which together with their mode of use are set forth by way of example in the following description, and which are particularly and distinctly pointed out and set forth in the appended claims forming part hereof.

The nature of the present invention may be stated in general terms as including a sealing

5

strip having lopsided or unsymmetrical U cross section, and which constitutes an improvement of such a sealing strip as set forth broadly and in detail in my said prior application, Serial No. 539,957.

The present improved sealing strip is preferably formed of spring metal, and has an unsymmetrical U cross section, and includes a bottom wall and a narrower leg wall and a broader wall extending from the opposite preferably parallel sides of the bottom wall. The leg walls are thus laterally spaced from each other, and the broader leg wall preferably includes reversely angled bands having sides parallel with each other and the sides of the bottom wall, and the narrower leg wall is transversely curved and its outer side is preferably sharp cornered for improved self-engagement in the retaining groove of the piece, element, or member in which it is mounted.

The present improvements also include improved combinations of the improved sealing strips with overlapping structural or building members, pieces, or elements, which are desired to be sealed, and which have a wide variety of specific forms and uses.

By way of example preferred embodiments of the improved sealing strip and improved combinations and subcombinations including the same, are illustrated in the accompanying drawings forming part hereof, in which

Fig. 1 is an enlarged oblique view of one of the improved sealing strips in its unrestrained condition as formed, and before being placed in self-engaging position in the groove of the strip holder member of overlapping or overlappable members;

Fig. 2, an enlarged fragmentary transverse sectional view showing the combination of one of the improved sealing strips with overlapping members;

Fig. 3, a fragmentary transverse sectional view of improved overlapping sheet metal members in combination with one of the improved sealing strips;

Fig. 4, a fragmentary transverse sectional view of another form of improved overlapping sheet metal members in combination with one of the improved sealing strips;

Fig. 5, a fragmentary transverse sectional view of improved cast or molded overlapping members in combination with one of the improved sealing strips;

Fig. 6, a fragmentary transverse sectional view showing a panel wall construction including a batten between adjacent panels, and the improved sealing strips combined with the batten and the panels;

Fig. 7, a fragmentary transverse sectional view showing a chest top construction and the like including the improved sealing strips;

Fig. 8, a fragmentary transverse sectional view showing a ship lap wall construction including the improved sealing strips;

Fig. 9, an outside elevation view of an improved outward swinging casement window construction, including the improved sealing strips;

Fig. 10, an enlarged fragmentary transverse sectional view thereof, as on line 10—10, Fig. 9;

Fig. 11, a similar view thereof, as on line 11—11, Fig. 9;

Fig. 12, a similar view thereof, as on line 12—12, Fig. 9;

Fig. 13, a similar view thereof, as on line 13—13, Fig. 9; and

Fig. 14, a fragmentary transverse sectional view similar to Fig. 10 of my said prior application, Serial No. 539,957, and showing a modified construction including the present improved sealing strip.

Similar numerals refer to similar parts throughout the drawings.

The improved sealing strip indicated generally by 15 is made of spring metal, preferably bronze, and has a transverse cross section which is generally that of a lopsided or unsymmetrical U, and includes a preferably parallel sided bottom wall 16, from the sides or substantially right angled corners 17 and 18 of which extend, respectively, preferably, parallel sided leg walls indicated generally by 19 and 20.

The outer side 21 of the leg wall 19 is preferably enlarged, which as shown, is effected by forming the sealing strip 15 from sheet metal and providing a back-folded band 22 at the leg wall outer side 21.

For the purposes of the present improvements, the outer side 23 of the leg wall 20 is sharp cornered which is effected by shearing or grinding the side 23.

The width of the leg wall 19 between its sides 17 and 21 is substantially greater than the width of the leg wall 20 between its sides 18 and 23. In other words the leg wall 20 is narrower than the broader leg wall 19.

In the leg wall 19, a central longitudinal flat band 19—1 is reversely angled with respect to the adjacent side by side flat bands 19—2 and 19—3.

For the purposes of the present improvements, the leg wall 20 is transversely curved; and the curvature is outwardly concave in the outer face 24 between the leg wall sides 18 and 23, and inwardly convex in the inner face 25 opposite the broader leg wall 19.

As shown in Figure 1, in unrestrained condition, as made, and before insertion into a holder member, in each lopsided U sealing strip 15, the wider or broader leg wall 19 has a substantial inclination towards the shorter or narrower leg wall 20 away from the plane perpendicular to the bottom wall 16 through the corner 17. Also, for the purposes of the present improvements, the outer side 23 of the narrower leg wall 20 is offset outwardly a substantial distance from its side or corner 18 common with the bottom wall, and the bottom wall is substantially radial with respect to the transversely curved narrower leg wall 20.

As shown, the bottom wall 16 is flat, but it may have any other desired form, such as a transverse overall curvature, corrugation, or the like.

In Fig. 2, one of the improved sealing strips 15 is shown in combination with overlapping members 26 and 27, the overlapping member 26 being a rabbet strip holder member, and having a rectangular sealing strip holder groove 28 formed in one rabbet face 29 thereof, which face 29 is at

right angles to the other rabbet face 30. The rabbet face 30 constitutes an extension of one side face 31 of the rectangular groove 28, which has an opposite side face 32 and a bottom face 33.

5 The rabbet face 30 is also the inside face of a flange 34 overlapping an opposite parallel face 35 of the member 27 which has another face 36 at right angles to the face 35 and parallel with the rabbet face 29 of the member 26. The face 36 of the member 27 also extends across the outer opening of the rectangular groove 28.

The construction and arrangement of these overlapping members 26 and 27 are substantially the same as the similar members shown in Fig. 4 of my said prior application, Serial No. 539,957.

One of the improved sealing strips 15 is inserted in the rectangular groove 28 with the bottom wall 16 of the strip abutting the groove bottom face 33, and with the strip broader leg wall 15 extending 20 out of the groove alongside the rabbet face 30 of the flange 34, and between the face 30 and the opposite face 35 of the overlapped member 27. The narrower leg wall 20 of the sealing strip 15 in the groove 28 is in self-engaging restrained position, with the outer sharp corner 23—1 of its outer side 23 abutting against the groove face 32.

If the material of the sealing strip holding member 26 is wood or other material softer than the spring metal from which the sealing strip 15 is 30 preferably made, then the sharp outer corner 23—1 of the outer side 23 of the narrower leg wall 20 will gouge into the adjacent groove face 32.

In Fig. 3 is shown a combination including improved overlapping sheet metal members 26—1 35 and 27—1 which are externally generally similar to the members 26 and 27, but in the sheet metal members 26—1, the groove 28—1 is provided with a flange 37—1 extending across the outer end of the groove face 32—1, providing an abutment 40 for the outer corner 23 of the improved sealing strip 15 located in the groove 28—1.

In Fig. 4, another form of improved overlapping sheet metal members 26—2 and 27—2 are shown in which both members are externally rabbeted. 45 In the member 26—2, the groove 28—2 in which is located a sealing strip 15, has a side face 32—2 sloping from the groove bottom face 33—2 towards the groove side face 31—2. The sloping groove side face 32—2 thus constitutes a sloping 50 detent for the curved sealing strip leg wall at 20.

In Fig. 5, the overlapping members 26—3 and 26—4 are formed of cast or molded material, and the groove 28—4 is provided with a retaining flange 37—4 similar in function to the retaining 55 flange 37—1. A sealing strip 15 is located in the groove 28—4.

In Fig. 6 is shown a panel wall construction indicated generally by 38 and including a stud 39 against one face of which are abutted spaced side 60 bands 40 of panels 41.

Between the spaced side faces of the panels 41 is located a T batten 42 including inner rabbets having laterally opening grooves 28—5 formed therein in each of which is located a sealing strip 65 15 in sealing abutment with one of the panel side bands 40.

In Fig. 7 is shown an improved construction for a chest top and the like including the improved sealing strips, and which includes walls forming 70 a chest 45 having an upwardly opening rectangular upper end indicated generally by 46 and which may be said to constitute a rectangular frame.

A cover top wall 47 extends across the upper 75 faces of the rectangular frame 46, and the top

wall 47 is provided on its under side with rectangular rabbets as shown, which overlap the members of the frame 46, and the rectangular rabbets of the top wall 47 are provided with horizontally opening or downwardly opening strip holder grooves 28-6 in each of which is located an improved sealing strip 15. The top wall 47 is connected by hinges 48 at one side with one of the members of the frame 46.

In Fig. 8 is shown a ship lap wall construction including the improved sealing strips, and which is indicated generally by 50 and includes studs 51, one of which is shown, upon which are nailed in the usual manner undersiding 52, and horizontally extending ship lap pieces or members 53 are nailed upon the siding 52.

Each ship lap piece or member 53 is modified from the usual form of ship lap and includes at its wider side a rabbeted outer band 26-7 which overlaps the outer band 27-7 of the adjacent member. Each rabbeted wider ship lap band 26-7 is provided with a strip holder groove 28-7 therein, in which is located one of the improved sealing strips 15.

In Figs. 9 to 13, inclusive, is shown an improved outwardly swinging casement window construction including the improved sealing strips, and in which the several sectional views Figs. 10 to 13, inclusive, each show an arrangement of overlapping members including a rabbeted member having a downwardly opening, or a horizontal opening, or a laterally opening holder groove 28-8 formed therein, in each of which is self-engaged one of the improved sealing strips 15.

In Fig. 14 is shown a combination of overlapping members for a separable frame for a built-in window frame and closures for the separable frame, and including the improved sealing strips hereof, the figure showing lower separable frame and closure members, and being generally similar to Fig. 10 by my prior application, Serial No. 539,957, but including a horizontally opening strip holder groove 28-9 with one of the improved sealing strips 15 therein, instead of the upwardly opening groove shown in my said prior application.

Thus, it will be seen that each of the above described combinations includes one or more sets of overlapping members, one of which is a rabbeted member having a strip holder groove formed therein and having one of the improved sealing strips self-engaging therein. The manifold adaptability of the fundamental combination of the overlapping members, one of which is a rabbeted member having a holder groove formed therein and one of the improved sealing strip self-engaging therein is thus clearly set forth.

The embodiments of the present invention illustrated and described herein are by way of example, and the scope of the present invention is not limited to the same or to the particular details thereof, but is commensurate with any and all novel subject matter contained herein which may at any time properly under the United States patent laws be set forth in the claims hereof or originating herein, and the elements of any of such claims are intended to include their functional or structural equivalents.

I claim:

1. In combination, a longitudinally extending member including a longitudinally extending flange and angled longitudinally extending faces forming a rabbet at one side of the flange, the member having formed therein a longitudinally extending sealing strip holding groove opening through one of the rabbet faces, and an unsymmetrical U sealing strip including a longitudinally extending flat bottom wall and longitudinally extending leg walls each having a side joined with a side of the bottom wall, one of the leg walls being transversely narrower than the other and being transversely curved, and the sealing strip self-engagingly fitting in the groove, the bottom wall and the narrower transversely curved leg wall being entirely within the groove with the flat bottom wall seated in the bottom of the groove and the wider leg wall extending at one side of the other rabbet face and being adapted for sealing abutment with a member overlapped by an outer sealing band portion of the wider leg wall.
2. In combination, a longitudinally extending member including a longitudinally extending flange and angled longitudinally extending faces forming a rabbet at one side of the flange, the member having formed therein a longitudinally extending sealing strip holding groove opening through one of the rabbet faces, and an unsymmetrical U sealing strip including a longitudinally extending flat bottom wall having laterally spaced longitudinally extending leg walls, one of the leg walls being transversely narrower than the other and being transversely curved, and the sealing strip self-engagingly fitting in the groove with the flat bottom wall seated therein, the narrower transversely curved leg wall being entirely within the groove and the wider leg wall extending at one side of the other rabbet face and being adapted for sealing abutment with a member overlapped by an outer sealing band portion of the wider leg wall, the groove having a face adjacent the transversely curved leg wall, and the transversely curved leg wall having a sharp cornered outer side adapted to engage with the adjacent face of the groove.
3. A sealing strip adapted for self-engagement in a longitudinally extending groove in a structural member and the like, the sealing strip having an unsymmetrical U cross section and including a longitudinally extending flat bottom wall and longitudinally extending leg walls each having a side joined by a substantially right angled corner with a side of the bottom wall, one of the leg walls being transversely narrower than the other and being transversely curved.
